AUTOMATIC FIDELITY CONTROL CIRCUITS

Rene A. Braden, Collingswood, N. J., assignor to
Radio Corporation of America, a corporation
of Delaware

Application November 29, 1933, Serial No. 700,247

9 Claims. (Cl. 250—20)

My present invention relates to fidelity control arrangements for radio frequency signalling systems, and more especially to automatic fidelity control circuits for radio receivers.

5 In my co-pending application Serial No. 682,743, filed July 29, 1933 there are disclosed, and claimed, various arrangements for automatically regulating the effective resonance curve of a tunable network in response to the variation in 10 amplitude of received signal energy. The essential aim of these arrangements is to control the selectivity of a radio frequency signalling system in such a manner that the system is more selective on weak signals than on strong ones with 15 the result that on strong local stations the selectivity is least, but on weak stations the receiver is most selective.

Now, in the present application there are disclosed further arrangements for automatically 20 varying selectivity and improving fidelity when receiving strong signals. In each of the present arrangements a double system of amplifiers is utilized, certain of the amplifiers being operative, in response to variations in amplitude of the received signal energy, to improve the selectivity of the receiver and impair its fidelity when receiving 25 distant station signals, and other of the amplifiers being operative to decrease the selectivity and improve the fidelity of the receiver when receiving strong signals as from local stations.

Hence, it may be stated that it is one of the main objects of the present invention to provide further automatic fidelity control arrangements, 30 the arrangements functioning to vary the fidelity of a radio receiver by utilizing, in response to variations in amplitude of received signal energy, amplifiers of predetermined selective characteristics.

40 Another important object of the present invention is to provide at least two parallel amplifiers in a radio receiver, one of which amplifiers has a sharp selective characteristic and the other has a broad characteristic, the receiver additionally 45 including means for differentially controlling the transmission efficiency of said amplifiers in such a manner that the amplifier of sharp selectivity is dominant when receiving weak signals, and the amplifier of broad selectivity predominates in action when receiving strong signals.

Another object of the invention is to provide in a radio receiver a push-pull selective amplifier which has a sharp resonance curve in normal operation, but which includes means for automatically rendering certain of the tubes of the push-

pull amplifier inoperative for broadening the resonance curve when receiving strong signals, as from local stations.

Still other objects of the invention are to improve generally automatic fidelity control circuits for radio receivers, and to provide such control circuits which are not only reliable in operation, but readily constructed and assembled in receivers.

The novel features which I believe to be characteristic of my invention are set forth in particularity in the appended claims, the invention itself, however, as to both its organization and method of operation will best be understood by reference to the following description, taken in connection with the drawings, in which I have indicated diagrammatically several circuit arrangements whereby my invention may be carried into effect.

In the drawings,

Fig. 1 diagrammatically shows an embodiment of the present invention,

Fig. 2 diagrammatically shows a modification of the arrangement shown in Fig. 1,

Fig. 3 shows another modification of the invention,

Fig. 4 shows still another modification of the invention.

Referring now to the accompanying drawings, wherein like reference characters in the different figures designate similar circuit elements, there is shown in Fig. 1, in purely conventional form, a radio receiving system embodying one form of the invention. The receiving system comprises a source of signal energy 1, which source may be the signal collecting means and radio frequency amplifier of a superheterodyne receiver. The source of signals is shown followed by a network 2 which may comprise a combined oscillator-detector circuit of any type well known to those skilled in the art, or a first detector upon which is impressed local oscillation energy from any well known type of local oscillator. In any case the circuit 1 in the output of the network 2 is tuned to the operating intermediate frequency 40 and is coupled, as at M₁, to the tunable input circuit II of the intermediate frequency amplifier 3, preferably of the screen grid type, the circuit II being tuned to the operating intermediate frequency.

45 The tube 3 includes in its anode circuit a resonant circuit III having one side thereof connected to a source of positive potential B (not shown), this tuned circuit being tuned to the operating intermediate frequency and being coupled, as at 50

M₂, to a circuit IV which is tuned to the operating intermediate frequency. The circuit IV is connected to the input electrodes of the second detector 4, and this tuned circuit includes a coil 5 5 in series with the tuning condenser and secondary winding of the coupling transformer **M**₂.

The coupling **M**₁ is less than critical so that the resonance curve at the grid of tube 3 is relatively sharp, and the same applies to **M**₂. Signal energy 10 of intermediate frequency is also fed to a screen grid tube 6 from the tuned circuit I through a path which includes the condenser 7. The cathode of tube 6 is connected to the low potential side of circuit I through ground, while the condenser 7 connects the high potential side of circuit I to the control grid of tube 6.

The anode circuit of tube 6 includes a resonant circuit V coupled, as at **M**₃, to a resonant circuit VI, the latter circuit being connected between the 20 input electrodes of the screen grid amplifier tube II, and the anode circuit of the tube II including a resonant circuit VII. The coil 5 of the rectifier input circuit IV is magnetically coupled to the circuit VII. Circuits V, VI and VII are tuned to 25 the operating intermediate frequency.

The direct current blocking condenser 15 provides a coupling path to the succeeding audio amplifier and/or reproducer for the audio component of the detected intermediate frequency energy. 30 The lead 16 connects the grid circuit of tube 3 to a source of gain control potential designated "AVC", and it is to be clearly understood that the source may be any rectifier arrangement well known to those skilled in the art, and commonly employed 35 for automatic volume control.

The resonance curve at the grid of tube 6 has a substantially flat top, and is broader than the resonance curve at the grid of tube 3. The control biases impressed upon tubes 6 and 3 through 40 leads 17 and 16 respectively are arranged to work differentially. The lead 17 is connected between the grid of tube 6 and another source of control potential. With an extremely strong signal the amplification through tube 3 is completely cut off, 45 and the signals come through tubes 6 and II. The outputs of tubes 3 and II are fed into the common input circuit IV of the detector 4, although these outputs of tubes 3 and II may be separately rectified and combined in the audio circuit.

50 The differential biasing of the sharp and broad amplifiers is such that the gain of the sharp amplifier is greater than that of the broad amplifier when weak signals are received, while the reverse is true when strong signals are received. In between these two conditions there will be a value 55 of signal strength at which the amplifiers have equal gains, and an intermediate degree of selectivity is obtained. The control means 16' feeding the grid of tube 3 may be a biased detector for example, and the plate direct current potential component of the latter would then be used to 60 reduce the gain of the sharp amplifier with high signal input. The control device 17' can be a grid lead detector, in which case at high signal input 65 the broad amplifier would operate at maximum gain because the plate direct current potential component is a minimum at such high input. With weak signal input the sharp amplifier operates with maximum gain, and the broad amplifier 70 has a minimum gain. Any other desired type of gain control devices could be used at 16' and 17' provided the action was similar.

75 It will be seen that there has been provided between the detector 4 and the first detector 2 two parallel amplifier systems, both operating at inter-

mediate frequency. One of these systems is of sharp selectivity, while the other system is of broad selectivity. The signal from the first detector can be made to go through either of these parallel amplifier systems, or to divide in any proportion and go through both amplifiers. The connections from the two control sources 16'—17' 5 to the two parallel amplifier systems function to differentially operate these parallel amplifier systems, and the differential biasing is accomplished 10 in dependence on the signal amplitude variations. This has the result that the selectivity and fidelity 15 of the receiver varies in accordance with the received signal strength.

To increase the variation of selectivity with 15 signal strength, one or more additional stages of amplification may be inserted between the tube 3 and the detector 4, and between the tube 6 and the rectifier 4. Where such additional stages are utilized the couplings in the system including tube 20 3 should be less than critical, while the couplings in the system including tube 6 should be greater than critical coupling.

In Fig. 2 there is shown a modification of the arrangement shown in Fig. 1 wherein the sharply 25 tuned intermediate frequency amplifier includes the tube 3 having its tuned input circuit II inductively coupled to the resonant circuit I, as at **M**₁. The sharp amplifier further includes an amplifier 3' which has its input circuit 18 coupled 30 to the tuned output circuit of tube 3, as at 19, the coupling 19 being less than critical coupling. A tuned circuit 20 is magnetically coupled to the tuned output circuit of tube 3', the circuit 20 functioning as a phase correcting circuit. The sharp 35 amplifier network ends with a circuit similar to that which begins the broad amplifier, and this makes the output phase angles of the two amplifiers similar.

The broadly tuned amplifier network includes 40 the tube 6 which is coupled to the tuned circuit I through the condenser 7, the control grid of tube 6 being connected to the gain control device 17' through lead 17. The cathode of tube 6 is grounded. The amplifier tube II succeeds the tube 6, 45 and the output from circuit VII is impressed upon a resonant circuit 21. The leads 16 and 17 are connected between the grid circuits of tubes 3 and 6 respectively as in the case of Fig. 1. The coupling **M**₃, and the coupling between circuits VII 50 and 21 is greater than critical coupling. A special tube 22 combines the outputs of the sharply tuned amplifier and the broadly tuned amplifier, the outputs of these two amplifiers being impressed upon the grids 23 and 23' of tube 22, these 55 two control grids being disposed in parallel relation.

The tube 22 includes a positive screen grid between the parallel grids 23, 23' and the anode of the tube. The anode circuit of tube 22 is coupled to the rectifier input circuit IV through a tuned circuit III. It is to be clearly understood that the anode circuit of tube 22 can also be connected to an additional intermediate frequency amplifier stage. The action of this circuit of 65 Fig. 2 is the same as in Fig. 1.

In Fig. 3 is shown another circuit arrangement for parallel sharp and broad amplifiers. In this circuit arrangement the sharp and broad amplifiers have the same type of input circuit. 70 No special circuits are required to correct the phase angles for this reason. Also, a different output combining circuit is shown utilizing two conventional screen grid tubes 3'' and 6'' with their anodes tied together by leads 40 and 41. 75

The common tuned circuit 42 has its high potential side connected to leads 40 and 41, and circuit 42 is magnetically coupled, as at 43, to the rectifier tuned input circuit IV.

5 The control biases are applied to the sharp and broad amplifiers through leads 16 and 17 respectively. In this modification the control lead 16 is connected to the control grids of the tubes 3, 3' and 3'' from the control device 16', while the 10 lead 17 is connected to the grids of tubes 6, 6' and 6'' from the control device 17'. The control biases are applied to the parallel amplifier systems in such a manner that these systems are controlled differentially in accordance with the 15 signal amplitude variations as described herefore.

Still another modification of the present invention is shown in Fig. 4. In this modification there is connected between the tuned input circuit IV of the detector 4 and the source of signal energy 1 a pair of cascaded tuned push-pull amplifier networks. The first of the cascaded stages comprises a pair of screen grid tubes 50 and 51 connected in push-pull relation, the signal 20 control grids being connected through condensers to opposite sides of the tuned input circuit 52, the midpoint of the inductor circuit 52 being connected to ground through a radio frequency condenser 53.

25 The tuned circuits 54 and 55 are connected in series between the anode of tube 50 and the anode of tube 51. Through a bias resistor 57 is furnished a fixed bias for the grid of tube 50, while through a resistor 57 is furnished control bias for the grid of tube 51. The second push-pull stage 30 comprises a pair of screen grid tubes 60 and 61. The ungrounded side of resistor 14 is connected to the control grid circuit of tube 60 through a lead 62, a lead 63 and grid resistor 64, while the 35 same point is connected to the control grid of tube 51 through a path which includes the lead 62, the lead 65 and the grid resistor 57.

30 A grid resistor 66 is connected between the cathode and grid of tube 61, a fixed source of grid 40 bias voltage being included therein. When tubes 50, 51, 60 and 61 are operating with equal control grid biases, the circuits 54 and 55, which are tuned to the carrier frequency, are effectively in parallel. In this condition the resonance 45 curve is the same as that of the ordinary form of amplifier employing one tuned circuit per stage. Now, if the biases on tubes 51 and 60 are increased so as to cut tubes 51 and 60 out of service, circuits 54 and 55 become a pair of coupled band pass circuits, tube 59 feeding into the 50 primary and tube 61 taking the signal from the secondary. If the coupling M has the right value a band pass characteristic is obtained in this stage. Of course, tubes 50 and 60 can be used 55 instead of tubes 50 and 61, but this will give less selectivity. It is desirable to hold the center-point of each grid circuit of the cascaded push-pull amplifier tubes at ground potential. The coils 70 and 71 are not tuned to signal frequency.

60 It will now be realized that there is shown in Fig. 4 an arrangement wherein a push-pull tuned amplifier, which is selective, is converted into a single tube coupled circuit system if certain tubes are made inoperative. When the signal amplifier 65 increases the ungrounded side of resistor 14 becomes more negative, with the result that the biases applied to the grid circuits of tubes 60 and 61 become sufficiently great to render these two tubes inoperative.

65 70 75 As explained above this results in a trans-

formation of the cascaded push-pull networks into a band pass amplifier network wherein the tube 50 couples the resonant circuit 52 to the coupled tuned circuits 54 and 55, the latter coupled tuned circuits having the band pass characteristic, and the tube 61 deriving energy from the coupled circuits 54, 55 through the secondary coil 70, 71. Thus, with strong signals the circuit has become less selective, but the fidelity has improved. The reverse action takes place when 10 weak signals are received.

15 While I have indicated and described several systems for carrying my invention into effect, it will be apparent to one skilled in the art that my invention is by no means limited to the particular organizations shown and described but that many modifications may be made without departing from the scope of my invention as set forth in the appended claims.

20 What I claim is:

1. In combination with a pair of amplifier circuits arranged in parallel, one of which has a sharp resonance characteristic, and the other has a broad resonance characteristic, a detector coupled to each of said amplifiers, and means, responsive to variations in the output currents of said detectors, for differentially regulating the gain of said amplifiers.

2. In combination with a pair of amplifier circuits, one of which has a sharp resonance characteristic, and the other has a broad resonance characteristic, a rectifier coupled to each of said amplifiers, and means, responsive to variations in the output currents of said rectifiers, for differentially regulating the transmission efficiency of 35 said amplifiers, and a tube coupling the rectifier input circuits to the output circuits of said amplifiers, said tube including at least two control grids, one of which control grids is connected to one of the amplifiers, and the other grid is connected to the remaining amplifier.

3. In a system as defined in claim 2, said control grids being arranged in parallel with each other, and a phase correcting circuit coupled to the output circuit of one of said amplifiers.

4. In an automatic fidelity control system for a radio receiver, a sharply tuned amplifier and a broadly tuned amplifier arranged in parallel, each of said amplifiers including an output tube, a resonant circuit, means for connecting the output 50 electrodes of said output tubes to the high potential side of said resonant circuit, a rectifier coupled to said resonant circuit, and a conductive connection between gain control electrodes of said parallel amplifiers and gain control means connected to the rectifier for differentially regulating the gain of said amplifiers.

5. In combination with a source of signalling energy and a rectifier adapted to convert impressed signal energy into direct current potential variations, an amplifier system comprising a pair of cascaded push-pull amplifier networks, said amplifier system including means for resonating the system to a desired carrier frequency, said system being constructed to have a sharply 60 selective high frequency response characteristic when receiving weak signals, and a conductive connection to at least one tube of each of the cascaded networks from the rectifier circuit for impressing on said tubes said direct current potential variation whereby said amplifier system is given a broad high frequency response characteristic when receiving strong signals.

6. In combination in a radio receiver, a source of signal energy, a signal demodulator, a signal 75

amplifier system coupled between said source and demodulator, said system comprising at least a pair of cascaded signal amplifier networks arranged in parallel, each of the networks including at least one resonant circuit tuned to the operating signal frequency and arranged to couple successive tubes of the networks, said networks being constructed and arranged to impart a sharp selectivity characteristic to the system when receiving weak signals and a relatively broad selectivity characteristic when receiving strong signals, and additional means responsive to variations in received signal amplitude for regulating the gain of predetermined tubes of said parallel networks to render one or the other of said characteristics predominant.

7. In a receiver as defined in claim 6, the said resonant circuits of said parallel networks being reactively coupled.

8. In combination with a sharply selective signal amplifier and a broadly tuned signal amplifier, a common signal source coupled to both amplifiers, a signal detector coupled to the outputs of said amplifiers, means for regulating the gain of the sharp amplifier, in response to received signal strength, in the inverse sense as the variation in received signal strength, and other means to regulate the gain of the broad amplifier in the same sense as said signal strength variation.

9. In a system as defined in claim 8, said regulating means comprising signal rectifiers.

RENE A. BRADEN.
